Application September 7, 1940, Serial No. 355,840

26 Claims. (Cl. 178—5.4)

1

This invention relates to television, especially to television in natural colors. The invention particularly contemplates the provision of a method of scanning and reproducing an image in natural colors which gives good color rendition and preserves detail in the image under widely varying color conditions, without requiring an excessive transmission band and without objectionable flicker. The invention also contemplates the provision of apparatus for scanning areas in accordance with the method of the invention.

It has heretofore been suggested to achieve color television by transmitting successively images corresponding to the primary colors in the object transmitted. The three-color system, employing red, green and blue filters, is usually employed. In this system each transmitted image represents the whole of the object scene as viewed through the corresponding filter, as distinguished from an interlaced scansion. The system is therefore open to the usual objection of excessive flicker, unless the images are transmitted at a high speed. The required high rate of transmission, since the images are complete, requires an excessive transmission band if detail is to be preserved. To reduce flicker, it has also been proposed to simultaneously transmit the red, green and blue images over separate channels, but such a system is undesirably complex.

A system for the interlaced scansion of images in color has also been suggested, but in this system each set of lines always represents the same color in the object field. With such a system, if the object field happened to be all red, for example, or predominantly red, only the red set of lines would be transmitted, the other set or sets of lines being negligible. Thus a considerable amount of detail would be lost.

In accordance with the present invention, image areas are scanned in a plurality of interlaced field scancions, successive field scancions corresponding to different primary colors. However, within a complete cycle, each set of interlaced lines represents each of the primary colors. With this system, if the color of the object field is predominantly one of the primary colors, that color will be successively transmitted by different sets of interlaced lines so that no detail will be lost. To accomplish this result, the sets of interlaced lines and the number of primary colors are made non-multiples of each other, and both the sets of lines and the primary colors alternate in regular sequence. For example, if three primary colors are employed, field scancions are

2

successively red, green and blue, this sequence being cyclically repeated. With three primary colors, either double or quadruple interlacing may be employed, or in general, any number of sets of lines which is a non-multiple of the number of primary colors. The several interlaced sets of lines are also scanned in regular cyclically recurring sequence.

By employing the system of the invention, excellent color rendition and adequate detail can be obtained within the present standard television band for black and white pictures without objectionable flicker. In some specific embodiments hereinafter described the theoretical resolution of the color images is somewhat less than that of black and white images, for the same band width. However, it is found that the effect on the eye of the addition of color satisfactorily compensates for the theoretical loss of resolution.

20 The invention will be more readily understood by reference to the drawings and to the following detailed description thereof.

In the drawings:

Fig. 1 represents schematically a double-interlaced scanning pattern;

Fig. 2 represents a scanning sequence suitable for use in a double-interlaced, three-color system;

Fig. 3 represents schematically a quadruple-interlaced scanning pattern;

Fig. 4 represents a scanning sequence suitable for use with a three-color, quadruple-interlaced system;

Fig. 5 illustrates diagrammatically a television color-film transmitter employing a continuously moving film, adapted for use with the scanning sequence of Fig. 2;

Figs. 6, 7 and 8 are detail views of elements of the scanning apparatus of Fig. 5;

Fig. 9 is a diagram illustrating the scanning of a film-frame during successive scansion periods;

Fig. 10 illustrates diagrammatically a color-film transmitter employing an intermittently moving film;

Fig. 11 illustrates a scanning sequence for the apparatus of Fig. 10 when transmitting in accordance with the system of Fig. 2; and

Fig. 12 illustrates diagrammatically a color television receiver adapted for use with the systems of the invention.

Fig. 1 illustrates a conventional double-interlaced scanning pattern composed of one set of lines *a*, and a second set of lines *b* interlaced with the *a* lines. The pattern is scanned in the usual manner, one set of lines, say the *a* lines, being

scanned from top to bottom in a so-called "field-scansion" period. The *b* lines are then scanned during the next field-scansion period. The frequency with which the scanning point returns to the starting corner is referred to as the "field frequency" and the transversal of the field as one field scansion, regardless of whether every second, fourth, etc. line is traced at each traversal. The frequency with which every line of the field is scanned is referred to as the "frame frequency" or "image frame frequency," this being one-half, one-quarter, etc., of the field frequency, depending on whether double, quadruple, etc., interlacing is used.

Referring to Fig. 2, a scanning system is illustrated for use with a double-interlaced, three-color system. The sawtooth wave represents the low-frequency or vertical scanning wave. Alternate scanning waves are marked *a* and the intervening scanning waves marked *b*, indicating the respective set of lines being scanned during that field scansion period. Below each wave is indicated, by way of example, the respective color being scanned at that time. The letters R, G and B are used to denote red, green and blue, these being selected as representative of a three-color system. Of course, other primary colors may be employed, if desired, in accordance with well known principles of color reproduction. It will be noted that the interlaced sets of lines cyclically recur in regular sequence, and that the colors cyclically recur in regular sequence. However, the first red image is formed by the *a* lines, and the second red image formed by the *b* lines. Similarly, each of the other colors is composed successively of *a* and *b* lines. After six scansion periods, each color has been reproduced by each set of lines, whereupon the cycle begins again.

For convenience, suitable legend has been placed on Fig. 2. The term "image field" is applied to a single scansion of one set of interlaced lines. The term "image frame" is applied to two field scansion periods during which both sets of lines are scanned, although they are scanned in different colors. The term "color field" is applied to the period during which each color is reproduced once, or the period between successive scensions of the same color, this being equal to three field scansion periods. The term "color frame" is applied to the period within which each color is reproduced by each set of lines.

At the present time the standards for black and white transmission call for the reproduction of pictures by double-interlaced scansion, with a field frequency of 60 field scans per second. This gives a frame frequency of 30 frames per second. In the present system, in order to improve color rendition without flicker, it is proposed to increase the field frequency to, say, 120 field scansion per second, thus making the image field period $\frac{1}{120}$ second. This gives an image frame period of $\frac{1}{60}$ second, a color field period of $\frac{1}{40}$ second, and a color frame period of $\frac{1}{20}$ second, as indicated in Fig. 2. These specific values are of course given for purposes of illustration only. If the field period were changed, the other periods would be changed accordingly.

With the specific values given in Fig. 2, all three colors are reproduced within $\frac{1}{40}$ second, each color being reproduced by one set of lines. Assuming the most disadvantageous case in which the image is all one primary color, say red, a red image will be reproduced by either the *a* or *b* lines at intervals of $\frac{1}{40}$ second, and a complete red image formed by both sets of lines will be

reproduced within $\frac{1}{20}$ second. Thus serious difficulties due to flicker are avoided. Also, no detail is lost since both set of lines are reproduced in this color. Of course, in most instances at least small amounts of the other primary colors will be present so as to assist in reducing flicker.

Assuming a transmission band width just sufficient to reproduce the full detail of 441 lines per frame for black and white pictures, in accordance with present standards, the equivalent resolution of the system of Fig. 2 will be

$$441\sqrt{\frac{1}{2}} = 312$$

lines per frame. Although the resolution for color is somewhat lower due to the fact that the field frequency has been increased, the addition of color compensates for the theoretically lower definition and yields a very satisfactory image. Of course, a wider band would permit greater definition.

Figs. 3 and 4 illustrate a quadruple-interlaced system. Such a system, although somewhat more complicated than the double-interlaced system of Fig. 2, has the advantage that it provides higher definition for the same band width. Fig. 3 illustrates the conventional system of quadruple-interlaced scansion. Lines *a* are first scanned from upper left to lower right, then the lines *b* half-way between the lines *a* are scanned from upper left to lower right, then lines *c* and lines *d*. Of course, the present invention is not limited to the scansion of the four sets of lines in the particular order given.

Fig. 4 illustrates a scanning sequence in which successive saw-tooth waves correspond to successive sets of lines. The image field period is assumed, for example, to be $\frac{1}{180}$ second. Successive sets of lines correspond to successive colors, yielding a color field period of $\frac{1}{60}$ second as shown. The image frame, during which each set of lines is scanned once, is $\frac{1}{15}$ second. A complete color frame, during which each color is reproduced by all of the four sets of lines, is $\frac{1}{15}$ second. Even if the image were all red, the fact that component red images recur at $\frac{1}{60}$ second intervals reduces flicker, and the fact that the red image is reproduced by all four sets of lines yields full definition.

Assuming again a band width just sufficient to reproduce 441 lines per frame at a double-interlaced field frequency of 60 field scans per second, as fixed by present standards, the equivalent definition for the color system of Fig. 4 would be $441\sqrt{\frac{1}{3}} = 360$ lines per frame. This represents an increase in definition over that of Fig. 2 for the same band width. As in the case of Fig. 2, further definition could be obtained by a broader band.

In Fig. 4, in parentheses, are given the periods for an assumed field scansion period of $\frac{1}{120}$ second. The color field is $\frac{1}{40}$ second, the image field $\frac{1}{30}$ second, and the color frame $\frac{1}{10}$ second. With such values, full 441 line definition could be obtained with present standards. To reduce interline flicker, the scanning lines could be increased to 550, for example.

It will be noticed that in both Figs. 2 and 4, the number of colors, namely three, is not a multiple of the number of sets of lines, which are two and four, respectively. Also, the number of sets of lines is not a multiple of the number of colors. This non-multiple relationship yields the advantageous result that each color is reproduced successively by a different set of lines. If

a different number of colors or a different number of sets of lines were employed, this non-multiple relationship could be preserved and the advantages of the present invention retained.

Fig. 5 illustrates a film scanner suitable for use with the systems of the invention. The apparatus is particularly designed for use with standard motion picture sound film requiring an average rate of reproduction of 24 film frames per second, and for use with the scanning system of Fig. 2. A film 10, threaded over sprockets 11, is driven with continuous uniform movement by motor 12 at the required rate of 24 film frames per second. The film is of the color type, for example, of the Technicolor or Kodachrome type. The film gate 13 is illuminated with light from a suitable projection source such as the arc 14 and condenser lens 15. Other sources of light could of course be employed. The film gate is longer than that of a single film frame in order to permit each film frame to be scanned a plurality of times during its travel through the gate. In the specific embodiment described, the film gate is designed to expose an area of the same width and $\frac{8}{5}$ the height of a film frame.

The system for projecting images from the film to the cathode 16 of the scanning tube 17, here shown as a tube of the Farnsworth "Image Dissector" type, is a modification of that shown in Figs. 13 and 14 of my copending application Serial No. 210,607, filed May 28, 1938, for "Method and apparatus for television," now Patent No. 2,287,033. As there described, the projection lens 18 is positioned to form an enlarged virtual image of the film in a plane behind the film, such as plane 19. Small lenses 1, 2, 3, 4 and 5 operate successively to project virtual images in the plane 19 to the cathode 16 of the image dissector. The small lenses 1-5 are rendered successively operative by the shutter disk 21 driven by motor 12. The shutter disk is illustrated in Fig. 6, and consists of an opaque disk having slots 1', 2', 3', 4' and 5' cut therein. As the disk rotates, these slots successively uncover the small lenses.

In the path of light from the film is positioned a color disk 22. This disk is illustrated as located between the plane of the film and the projection lens 18. However, it might also be placed on the opposite side of the film or at any convenient location between the plane of the film and the cathode 16 of the image dissector. The disk should be designed and located so that the cathode 16 is illuminated with light of successive primary colors during successive field scans. When positioned as shown, the disk may be constructed as shown in Fig. 7. The disk should be large enough so that each filter segment R, G, B successively covers the film gate, and large enough so that the transfer from one color sector to the next takes place during a blanking period. If desired, the filter segments may be constructed in the manner described in my copending application Serial No. 355,839, filed concurrently herewith, now Patent No. 2,304,081. An infrared filter 20 is placed in the path of light to the scanning tube, since photoelectric surfaces are usually sensitive to infrared and thus correct color rendition would be impaired.

It is desirable to employ a rather intense projection light beam so as to highly illuminate the cathode 16 of the image dissector and hence produce a favorable signal-to-noise ratio. In order to prevent the heat from such an intense projection source from adversely affecting the film, a heat disk 23, driven by motor 12, is advantage-

ously employed. The heat disk is illustrated in Fig. 8.

It will be understood that with a scanning device of the non-storage type it is necessary to illuminate a line of the film only at the time that particular line is being scanned. The heat disk therefore contains slots 1", 2", 3", 4" and 5", extending through equal central angles, one for each of the small projection lenses 1-5. For the specific case illustrated, slots 1" and 5" are continuations of each other. For a different specific embodiment this might not be true. The width of the slots is such as to expose only a fraction of a film frame to light from the projection source at any one time. In the limiting case this might be one line, but to avoid difficulties due to curvature of the slots and the necessity of maintaining very accurate phase relationships, the slots are preferably made wide enough to cover a number of scanning lines at a time. The construction of the slots will be explained more fully hereinafter, after consideration has been given to the manner in which the film is scanned.

Referring to Fig. 9, two adjacent film frames 25 and 26 are illustrated in the positions which they occupy in the film gate during five successive field-scans periods I, II, III, IV and V of film frame 25, and I' of film frame 26. It will be understood that since the film-frame period is $\frac{1}{24}$ second and the field-scans period $\frac{1}{120}$ second, five field scans will take place during one film-frame period. Also, the film frame moves downwardly a distance of $\frac{1}{5}H$, where H is the height of a film frame, during each field scan period.

At the beginning of the first field-scans period, the film frame 25 is in the position shown at I. Small lens 1 is rendered operable by slot 1' in the shutter disk and the image of film frame 25 is projected onto the cathode 16 of the image dissector. The electron image in the image dissector is deflected by suitable means (conventional and therefore not shown) to scan horizontal lines of the film frame at line-scanning frequency. The electron image is also deflected by suitable means (not shown) in a vertical direction to scan the image in a vertical direction at field-scanning frequency.

Since the film is continuously moving downwardly, the vertical deflection of the electron image need be only $\frac{1}{5}H$, in order to scan the full height of the film frame during the scans period. At the end of the first field scan the film frame 25 has reached the position shown at II. Projection lens 2 is thereupon rendered operable by slot 2' of the shutter disk and the same film frame rescanned from bottom to top. Since double interlacing is employed, the field scan I will be of one set of lines, say the a lines, and field scan II will be of the b lines. The required interlacing may be produced in the usual manner. At the end of field scan II, the film frame 25 will be in position shown at III. The a lines of the same film frame will then be rescanned from bottom to top. This procedure is repeated for the remaining field scan periods IV and V. The cycle is then repeated and the next film frame 26 scanned in similar manner. It will be noted that the b lines of film frame 26 will be scanned during the first field scan period I'. Successive field scans will alternate between a lines and b lines. The dotted lines of Fig. 9 indicate diagrammatically the deflection of the scanning beam.

As explained in my copending application

Serial No. 210,607, supra, the scanning area on the cathode of the image dissector remains unchanged for successive field scansions, except for the slight displacement required to produce interlacing. The displacement required to scan the same film frame five times during its continuous movement through the apparatus is produced by the separation of the small lenses 1-5.

During field scan I the image is projected through the red sector R of the color disk 22. During scan period II the image is projected through the green filter, and through the blue filter for scan period III. The colors are then repeated for successive field scan periods, R and G being operable for scan periods IV and V. The blue filter B is operable during field scan I' of the next film frame 26. It will be noted that for any given film frame, two colors are reproduced by both sets of interlaced lines but the third color by only one set. The particular color reproduced in only one set of lines changes for successive film-frame periods, and the single color reproduction alternates between *a* and *b* lines. Therefore no difficulty arises.

Continuing the description of the heat disk of Fig. 8 in conjunction with Fig. 9, slot 1" is operable during field scan I. The beginning of the slot exposes the lower lines of the film frame 25 and as the heat disk rotates, slot 1" progresses toward the top of the film frame to expose areas as they are scanned. Since the film frame moves downward $\frac{1}{5}H$ during the field scan period, the end of the slot need be displaced radially only $\frac{1}{5}H$ with respect to the beginning thereof. For scan period II, slot 2" operates and exposes film frame 25 in the same manner as in the previous scan period, the slot beginning at the bottom of the film frame and progressing toward the top as the disk rotates. The beginning and end of slot 2" is displaced inwardly a radial distance of $\frac{1}{5}H$ with respect to the beginning and end of slot 1", to compensate for the displacement of the continuously moving film during the first scan period. Slots 3", 4" and 5" are positioned in a similar manner to expose film frame 25 during respective scan periods III, IV and V. Corresponding points of successive slots will be displaced inwardly a radial distance of $\frac{1}{5}H$ to compensate for film movement. At the end of the film frame period, slot 1" again comes into operation to expose the succeeding film frame 26 during field scan I' of that film frame, etc.

The shutter disk 21, the color disk 22, the heat disk 23 and the film 10 are all driven by the same motor 12, in order to preserve proper synchronous relationships. For the specific embodiment disclosed, the field frequency is 120 field scans per second, the film is driven at a rate of 24 film frames per second, shutter disk 21 rotates at 1440 R. P. M., the color disk 22 at 2400 R. P. M. and the heat disk 23 at 1440 R. P. M. Suitable coupling means are provided between the several disks, the film drive and the motor to secure these relationships. Also, the deflection system (e. g., a saw-tooth wave generator) and the motor are maintained in synchronous relationship.

As shown in Fig. 9, the film gate needs to be $\frac{5}{6}H$ in height, in order that each film frame may be scanned five times as it passes through the apparatus.

It will be clear that the apparatus of Fig. 5, as described, operates to scan the film in accordance with the scanning system of Fig. 2, and yields a

video signal of which successive portions represent different color aspects and different sets of lines of an object field, as will be clear from Fig. 2. It should be pointed out that the term "image frame" is not synonymous with "film frame," nor is the term "frame-scanning frequency" identical with "film-frame frequency." Image frame period relates to the scanning of a field in both *a* lines and *b* lines, and frame-scanning frequency relates to the frequency of repetition of both *a* lines and *b* lines. On the other hand, film-frame period relates to the period during which a single film frame is scanned, and film-frame frequency relates to the rate at which film frames pass through the apparatus. The difference will be clear by consideration of Figs. 2 and 9.

The heat disk 23 may be employed in other types of film scanners wherein it is desired to expose only a portion of the film frame area at any one time, the particular area exposed progressing as scanning proceeds. The number of slots and shape of the slots may be altered in accordance with the particular scanning device with which it is used.

Referring to Figs. 10 and 11, apparatus is shown employing an intermittently moving film. Film 10 is drawn through gate 13 by an intermittent film moving mechanism of suitable construction, not shown. In this embodiment the film gate need expose only the area of one film frame. The film in the gate is illuminated by a suitable projection source such as the arc 14 and condenser lenses 15. Images in the film gate are projected by lens 31 to the mosaic 32 of the scanning device, here shown as a tube 33 of the storage type. As examples of such tubes, the "Iconoscope" and "Orthicon" may be mentioned. Suitable scanning means (not shown) for scanning the mosaic in horizontal and vertical directions are provided.

Since the scanning tube is a storage device, it is desirable to project the image onto the mosaic 32 only during the blanking period. Therefore a 45 flashing shutter 34 driven by motor 35 is provided. Shutter 34 is opaque, and has openings therein at suitable intervals so that as the disk rotates, the mosaic is periodically exposed to light from the film image. Preferably the openings are 50 of such shape as to expose all parts of the mosaic equally, as is known in the art. A color filter disk 36, which may be of the same type as shown in Fig. 7, is also disposed in the path of light from the image to the mosaic. If desired, it could of 55 course be placed near the plane of the film on either side thereof as shown in Fig. 5.

Fig. 11 illustrates diagrammatically the scanning procedure. At the left of the figure, V' represents the last field scan of a given film frame. During the blanking period immediately preceding this scan, the field frame is projected through the blue filter B by a light pulse 37. The light pulse should be of sufficient intensity to adequately expose the mosaic of the 60 scanning tube even though the duration of the pulse is very short. The *b* lines of the film frame are scanned during this field scan. During the scanning, the film is moved to the next film frame.

At the end of the field scan V', the succeeding film frame is projected onto the mosaic through the red filter R by a light pulse 38. The *a* lines of the film frame are thereupon scanned during scan period I. During the next blanking period the mosaic is exposed momentarily

through the green filter G and the b lines scanned during field scanion II. Scanion proceeds during periods III, IV and V in the manner indicated in Fig. 11. During scanion period V the film is moved to the next film frame, and the scanning procedure repeated beginning with I'', except that the b lines are scanned first.

The scanning system of Fig. 4, when an image field period of $1/180$ second is used, is not as conveniently adapted for use with the usual commercial motion picture sound film as that of Fig. 2, since the field scanion period of $1/180$ second is not as conveniently related to the film frame frequency of 24 frames per second. The system may of course be used with specially recorded film designed for use with the system. With an image field period of $1/120$ second, the system of Fig. 4 may conveniently be used with ordinary sound motion picture film. Both the systems of Figs. 2 and 4 may be used with direct pickup devices.

Fig. 12 illustrates receiving apparatus suitable for reproducing images in color in accordance with the systems described hereinbefore. The cathode-ray reproducing tube 41, which may be of conventional type, is provided with the usual pair of horizontal deflecting plates 42 and vertical deflecting plates 43. These are suitable for electrostatic scanning and may, of course, be replaced by corresponding coils for electromagnetic deflection. The horizontal deflecting plates 42 are energized by the saw-tooth generator 44 at line-scanning frequency, and the vertical deflecting plates 43 are energized by generator 45 at field-scanning frequency. Conventional means may be employed for securing double, quadruple or other interlaced scanning patterns in accordance with the invention. These are known in the art and hence need not be described in detail. An electron beam generated by the electron gun 46 is deflected by the pairs of plates and scans a field on the end of the tube. The end of the tube is covered with fluorescent material 47 to reproduce visual images.

In front of the tube, and preferably closely adjacent thereto, is positioned a color filter disk 48. This disk may be of the form shown in Fig. 7, and is rotatable about axis 49 by a motor 51. The motor is synchronized with the field scanning, and the driving ratio between the motor and the disk is selected with respect to the number of color sectors so that successive interlaced images are exhibited through successive color sectors. That is, the filter sectors traverse the end of the tube at field-scanning frequency. The disk should be of large enough diameter to obscure the scanning lines on the fluorescent screen at the time they are scanned. Also, it is advantageous to have the lines obscured for a considerable interval after scanning, so that the lines are exhibited through the proper color filter during the period of afterglow. The filter disk may advantageously be constructed in the manner described in my copending application, Ser. No. 355,081, filed concurrently herewith, now Patent No. 2,304,081.

For transmitters employing storage tubes, instead of employing an intermittently moving film, a continuous film projector which projects a stationary image could be employed.

It will now be appreciated that the present invention provides scanning systems of general utility for both direct pickup and film scanning, and at receivers. It will be understood that the scanning systems are not confined to use with the

particular apparatus described herein, the apparatus being for purposes of illustration only. Modifications are of course possible which come within the spirit and scope of the invention as described and claimed herein.

What I claim is:

1. In color television, the method of scanning a field which comprises scanning said field in a plurality of interlaced field scanions, successive interlaced field scanions corresponding to different colors of a plurality of primary colors, said plurality of primary colors and said plurality of interlaced field scanions being non-multiples of each other.
- 15 2. In color television transmitting and receiving systems, the method of scanning which comprises scanning a field in a plurality of cyclically recurring interlaced field scanions, successive field scanions corresponding to different colors of a plurality of cyclically recurring primary colors, said plurality of primary colors and said plurality of interlaced field scanions being non-multiples of each other and said field scanions recurring at the rate of at least 120 fields per second, whereby each set of interlaced scanning lines cyclically corresponds to each of said primary colors and objectionable color flicker may be avoided.
- 20 3. In color television transmitting and receiving systems, the method of scanning which comprises successively scanning a plurality of interlaced sets of lines of a field during respective successive field scanion periods, successively scanned sets of lines corresponding to different colors of a plurality of cyclically recurring primary colors, said plurality of interlaced sets of lines and said plurality of primary colors being non-multiples of each other and said field scanions recurring at the rate of at least 120 fields per second, whereby each set of interlaced scanning lines cyclically corresponds to each of said primary colors and objectionable color flicker may be avoided.
- 25 4. In color television transmitting and receiving systems, the method of scanning which comprises cyclically scanning a field in two interlaced sets of lines at the rate of at least 120 field scanions per second, said sets of lines being successively scanned during respective field scanion periods to form a double interlaced scanning pattern, said field scanions corresponding successively to three cyclically recurring primary colors, whereby each primary color cyclically corresponds to each set of interlaced lines and objectionable color flicker may be avoided.
- 30 5. In color television transmitting and receiving systems, the method of scanning which comprises cyclically scanning a field in four interlaced sets of lines at the rate of at least 120 field scanions per second, said sets of lines being successively scanned during respective field scanion periods to form a quadruple interlaced scanning pattern, said field scanions corresponding successively to three cyclically recurring primary colors, whereby each primary color cyclically corresponds to each set of interlaced lines and objectionable color flicker may be avoided.
- 35 6. In television, the method of transmitting and reproducing images in color which comprises scanning an object field at the transmitter in a plurality of interlaced field scanions to thereby generate a video signal, successive interlaced field scanions corresponding to different colors of a plurality of primary colors, said plurality of primary colors and said plurality of interlaced field scanions being non-multiples of each other, transmitting said video signal to a reproducer,
- 40 75

11

and reproducing from said video signal by said reproducer successive interlaced images corresponding to successive interlaced field scansions, successive interlaced images being reproduced in respective different colors of a plurality of primary colors, said plurality of interlaced images and said plurality of primary colors at the reproducer being non-multiples of each other.

7. In color television, a transmitting scanning device for scanning an image field in a plurality of interlaced field scansions, successive interlaced field scansions corresponding to different colors of a plurality of primary colors, said plurality of primary colors and said plurality of interlaced field scansions being non-multiples of each other, means for transmitting signals corresponding to said field scansions to a receiver, and means at said receiver for reproducing from said signals interlaced field scansions in colors respectively corresponding to said field scansions.

8. In color television, means for projecting a light image of an object field to a transmitting scanning device, means associated with said scanning device for scanning said object field in a plurality of successive interlaced field scansions at the rate of at least 120 field scansions per second, means for successively interposing in the path of light of said scanning device during successive field scanion periods a plurality of different color filters, said plurality of interlaced field scansions and said plurality of color filters being non-multiples of each other, means for transmitting signals corresponding to said field scansions to a receiver, a reproducing scanning device at said receiver adapted to reproduce from said signals interlaced field images corresponding to said interlaced field scansions, and means associated with said reproducing scanning device for exhibiting successive field images in colors respectively corresponding to said field scansions, whereby improved color rendition may be obtained and objectionable color flicker avoided.

9. In a color television transmitter, the combination which comprises scanning means for scanning an image field in a plurality of interlaced field scansions at the rate of at least 120 field scansions per second, means associated with said scanning means for successively presenting different color aspects of said image field to the scanning means during respective field scanion periods, the means for presenting different color aspects being correlated with the scanning means so that each of said color aspects is cyclically scanned by different sets of interlaced lines, whereby a signal providing improved color rendition without objectionable color flicker may be obtained.

10. In a color television transmitter, the combination which comprises scanning means for scanning an image field in a plurality of interlaced field scansions, means associated with said scanning means for successively presenting a plurality of primary color aspects of said image field to the scanning means during respective field scanion periods, said plurality of primary colors and said plurality of interlaced field scansions being non-multiples of each other and said field scansions recurring at the rate of 120 per second or more, whereby each color aspect is cyclically scanned by different sets of interlaced lines to improve color rendition and objectionable color flicker is avoided.

11. In a color television transmitter, the combination which comprises a scanning device for scanning an image field in a plurality of cyclically

12

recurring interlaced field scansions at the rate of 120 field scansions per second or more, means associated with said scanning device for successively presenting a plurality of cyclically recurring primary color aspects of said image field to the scanning device during respective field scanion periods, said plurality of primary colors and said plurality of interlaced field scansions being non-multiples of each other so that each color aspect is cyclically scanned by different sets of interlaced lines, whereby a signal providing improved color rendition without objectionable color flicker may be obtained.

12. In a color television transmitter, the combination which comprises scanning means for successively scanning a plurality of interlaced sets of lines of an image field during respective successive field scanion periods, means associated with said scanning means for successively presenting a plurality of cyclically recurring primary color aspects of said image field to said scanning means during respective successive field scanion periods, said plurality of primary colors and said plurality of interlaced sets of lines being non-multiples of each other and said field scansions recurring at the rate of 120 per second or more, whereby each set of interlaced scanning lines cyclically corresponds to each of said primary colors to improve color rendition and objectionable color flicker is avoided.

13. In a color television transmitter, the combination which comprises a scanning device for successively scanning a plurality of interlaced sets of lines of an image field during respective successive field scanion periods, a color filter device interposed in the path of light to said scanning device and adapted to expose said scanning device successively to different colors of a plurality of primary colors of said image field, said plurality of primary colors and said plurality of interlaced sets of lines being non-multiples of each other, and means for synchronizing said color filter device and said scanning device to expose said scanning device to said different colors successively during respective successive field scanion periods, whereby each set of interlaced scanning lines cyclically corresponds to each of said primary colors, said field scansions recurring at the rate of 120 per second or more to avoid objectionable color flicker.

14. In a color television transmitter, the combination which comprises a scanning device for cyclically scanning an image field in two sets of interlaced lines, said sets of lines being successively scanned during respective field scanion periods at the rate of at least 120 field scansions per second to form a double interlaced scanning pattern, means associated with said scanning device for successively presenting to said scanning device three cyclically recurring primary color aspects of said image field during respective successive field scanion periods, whereby each primary color is cyclically scanned by each set of interlaced lines to improve color rendition and objectionable color flicker is avoided.

15. In a color television transmitter, the combination which comprises a scanning device for cyclically scanning an image field in four sets of interlaced lines, said sets of lines being successively scanned during respective field scanion periods at the rate of at least 120 field scansion per second to form a quadruple interlaced scanning pattern, means associated with said scanning device for successively presenting to said scanning device three cyclically recurring pri-

13

many color aspects of said image field during respective successive field scansion periods, whereby each primary color is cyclically scanned by each set of interlaced lines to improve color rendition and objectionable color flicker is avoided.

16. In a color television receiver, the combination which comprises scanning means for reproducing images in a plurality of successive interlaced field scans at the rate of at least 120 field scans per second, means associated with said scanning means for presenting successive field scans in different primary colors, said means for presenting different primary colors being correlated with said scanning means so that each of said primary colors is successively presented by different sets of lines of the interlaced field scans, whereby improved color rendition may be obtained and objectionable color flicker avoided.

17. In a color television receiver, the combination which comprises scanning means for reproducing images in a plurality of successive interlaced field scans, means associated with said scanning means for presenting field scans in a plurality of successive primary colors during respective field scansion periods, said plurality of primary colors and said plurality of interlaced field scans being non-multiples of each other and said field scansion recurring at the rate of at least 120 per second, whereby each color cyclically corresponds to different sets of interlaced lines to improve color rendition and objectionable color flicker is avoided.

18. In a color television receiver, the combination which comprises a scanning device for reproducing images in a plurality of successive cyclically recurring interlaced field scans, means associated with said scanning device for presenting field scans in a plurality of cyclically recurring primary colors during respective field scansion periods, said plurality of primary colors and said plurality of interlaced field scans being non-multiples of each other and said field scans recurring at the rate of at least 120 per second, whereby each color cyclically corresponds to different sets of interlaced lines to improve color rendition and objectionable color flicker is avoided.

19. In a color television receiver, the combination which comprises a scanning device for successively reproducing a plurality of interlaced sets of lines of an image during respective successive field scansion periods recurring at the rate of at least 120 per second, means associated with said scanning device for successively presenting said interlaced sets of lines in a plurality of cyclically recurring primary colors during respective successive field scansion periods, said plurality of primary colors and said plurality of interlaced sets of lines being non-multiples of each other, whereby each set of interlaced lines is cyclically presented in each of said primary colors to improve color rendition and objectionable color flicker is avoided.

20. In a color television receiver, the combination which comprises a scanning device for successively reproducing a plurality of interlaced sets of lines of an image during respective successive field scansion periods, a color filter device positioned and adapted to present said interlaced sets of lines successively in different colors of a plurality of primary colors, said plurality of primary colors and said plurality of interlaced sets of lines being non-multiples of each other, and means for synchronizing said

14

color filter device and said scanning device to present said different colors successively during respective successive field scansion periods, said field scansion periods recurring at the rate of 120 per second or more, whereby each set of interlaced lines is cyclically presented in each of said primary colors to improve color rendition and objectionable color flicker is avoided.

21. In a color television receiver, the combination which comprises a scanning device for reproducing an image in two sets of interlaced lines, said sets of interlaced lines being successively reproduced during respective successive field scansion periods recurring at the rate of 120 per second or more to form a double interlaced image, means associated with said scanning device for successively presenting said sets of interlaced lines in three cyclically recurring primary colors during respective successive field scansion periods, whereby each primary color is cyclically presented by each set of interlaced lines to improve color rendition and objectionable color flicker is avoided.

22. In a color television receiver, the combination which comprises a scanning device for reproducing an image in four sets of interlaced lines, said sets of interlaced lines being successively reproduced during respective successive field scansion periods recurring at the rate of 120 per second or more to form a quadruple interlaced image, means associated with said scanning device for successively presenting said sets of interlaced lines in three cyclically recurring primary colors during respective successive field scansion periods, whereby each primary color is cyclically presented by each set of interlaced lines to improve color rendition and objectionable color flicker is avoided.

23. An interlaced multiple-color television scanning system comprising, means for periodically scanning the image to be transmitted or reconstructed in frames of n interlaced fields, and means for periodically changing the color of illumination associated with successive fields not greater than m times per field and in a series of m colors, the ratios of n to m and of m to n both being non-integral so that corresponding fields of successive frames are associated with illumination of different colors.

24. In color television, the method of scanning a field which comprises scanning said field in a plurality of interlaced field scans, successive interlaced field scans corresponding to different colors of a plurality of primary colors, said plurality of primary colors and said plurality of interlaced field scans being non-multiples of each other and said field scans recurring at the rate of at least 120 fields per second to avoid objectionable color flicker.

25. In television, the method of transmitting and reproducing images in color which comprises scanning an object field at the transmitter in a plurality of interlaced field scans at the rate of at least 120 field scans per second to thereby generate a video signal, successive interlaced field scans corresponding to different colors of a plurality of primary colors, said plurality of primary colors and said plurality of interlaced field scans being non-multiples of each other, transmitting said video signal to a reproducer, and reproducing from said video signal by said reproducer successive interlaced images corresponding to successive interlaced field scans, successive interlaced images be-

15

ing reproduced in respective different colors of a plurality of primary colors, said plurality of interlaced images and said plurality of primary colors at the reproducer being non-multiples of each other, whereby improved color rendition may be obtained and objectionable color flicker avoided.

26. In color television, a transmitting scanning device for scanning an image field in a plurality of interlaced field scansions at the rate of at least 120 field scansions per second, successive interlaced field scansions corresponding to different colors of a plurality of primary colors, said plurality of primary colors and said plurality of interlaced field scansions being non-multiples of each other, means for transmitting signals corresponding to said field scansions to a receiver, and means at said receiver for reproducing from said signals interlaced field scansions in colors respectively corresponding to said field scansions, whereby improved color rendition may be obtained and objectionable color flicker avoided.

PETER C. GOLDMARK.
